UNITED STATES PATENT OFFICE.

JAMES C. CURTIS AND JAMES B. COOK, OF BECKLEY, WEST VIRGINIA.

SHADE-BRACKET CORD HOLDER.

Application filed July 18, 1927. Serial No. 206,638.

The invention relates to shade brackets particularly adapted for use in connection with shade rollers of the non spring type and which rollers are provided with drums 5 around which a cord extends, and has for its object to provide a shade bracket formed from sheet metal and provided with an outwardly extending flange at one side thereof having a pintle receiving aperture and the 10 body of the bracket below the roller with a struck out portion forming spaced V-shaped slots through which the shade cord extends and freely moves when centrally disposed in relation to the slots and in the ends of which 15 slots the shade cord jams and is held when moved to the right or left, thereby holding the shade in any desired position.

A further object is to provide a transversely adjustable member adapted to arch 20 the side facing of a window frame for holding the lower end of the bracket against displacement.

A further object is to provide opposite 25 edges of the bracket with registering recesses for the reception of hooked members, which hooked members are adapted to receive the curtain and over drapery rods. Also to provide the hooked members with an angular portion adapted to overlie the upper side of 30 the window frame for additionally bracing the device.

With the above and other objects in view the invention resides in the combination and arrangement of parts as hereinafter set 35 forth, shown in the drawing, described and claimed, it being understood that changes in the precise embodiment of the invention may be made within the scope of what is claimed without departing from the spirit 40 of the invention.

In the drawing:—

Figure 1 is a view in elevation of the upper portion of a window frame showing the brackets applied thereto.

Figure 2 is a perspective view of one of the brackets.

Figure 3 is a horizontal sectional view through one of the brackets taken on line 3—3 of Figure 2.

Figure 4 is a vertical transverse sectional view through one of the brackets.

Figure 5 is a perspective view of one of the lower ends of one of the brackets showing the cord holding means.

Referring to the drawing, the numeral 1 designates a conventional form of shade

roller of the non spring type and at one end thereof is provided with a drum 2 around which drum a cord 4 extends. Upon a downward movement of the cord the roller is rotated in the direction of the arrow *a*, thereby winding the shade 5 on the roller 1. The shade is lowered manually in the usual manner by imparting a pull thereon which will rotate the roller 1 in the direction of the arrow *b*. In devices of this character it is necessary to provide means for holding the cord 4 for supporting the shade at various elevations and at the same time, on account of the cost of manufacture the mechanism 60 for holding the cord, necessarily must be small and to accomplish this result, one of the shade brackets 6 has its body portion 7 below the roller 1 provided with a struck out V-shaped portion 8, which forms V-shaped 65 slots 9. The cord 4 extends behind the struck out V-shaped portion 8 and through the slots 9, and when in intermediate position as shown in Figure 4, the cord may easily move upwardly and downwardly for adjusting the shade. However, when it is desired to hold 70 the cord 4 against movement after an adjustment thereof, it will only be necessary for the operator to grasp the free end of the cord 4 and move the same to the right or left until 75 it jams in the restricted ends of the V-shaped slots 9. By providing two V-shaped slots 9, it will be seen that there will be a double jamming of the cord 4, consequently slipping 80 of the cord obviated.

Brackets 7 are provided with outwardly extending integral flanges 10, which are provided with pintle receiving apertures 11 for the reception of the pintles 12 of the roller, and in which apertures the pintles 12 rotate 85 during the winding or unwinding of the shade 5.

Secured to the rear sides of the brackets 7 are transversely disposed members 13 having registering slots 14 through which extend 100 headed bolts 15. The headed bolts have their heads 16 engaging the rear sides of the members 17 whereby when the nuts 18 are tightened the telescopically engaged members will be held in adjusted positions where their angularly disposed arms 19 will overlie the sides of the window facings 20, and it will be seen 105 that when the set screws 21 are tightened the members 13 will be securely clamped to the window facings 20 thereby preventing side 110 displacement of the brackets. The arms 19 through which the set screws 21 are screwed

are preferably reinforced by right angularly shaped braces 22.

Brackets 7 extend upwardly and have their opposite edges provided with recesses 23, thereby forming lugs 24 under which the hooks 27 carried by the right angularly shaped members 28 engage and additionally support the brackets when their arms 29 are in engagement with the upper side of the window facing. The hooks 27 have reduced upwardly extending portions 30, which receive the ends of conventional forms of drapery rods 31, therefore it will be seen that the members 28 not only assist in supporting the brackets, but also form means for receiving and supporting the drapery rods 31.

From the above it will be seen that a curtain bracket is provided, which is simple in construction, may be easily and quickly ap-

plied to a window frame without varying the construction thereof, or marring the frame, and the device may be cheaply manufactured and sold.

The invention having been set forth what is claimed as new and useful is:—

A shade roller cord holder carried by a shade bracket, said cord holder comprising a struck out V-shaped member carried by the bracket and forming spaced V-shaped recesses having restricted ends, whereby when a cord disposed behind the struck out V-shaped member is moved to one side of the center thereof said cord will be gripped and held.

In testimony whereof we hereunto affix our signatures.

JAMES C. CURTIS.

JAMES B. COOK.
